(57) **CLAIM**

The ornamental design for a storage water heater, as shown and described.

DESCRIPTION

FIG. 1 is a top, front and right side perspective view of a storage water heater showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1; and,

FIG. 10 is an enlarged view of portion 10 in FIG. 3.

The broken lines in the drawings illustrate portions of the storage water heater which form no part of the claimed design.

The broken lines encircling portions of the storage water heater in FIGS. 1 & 3 and illustrated in enlarged views in FIGS. 9 & 10 form no part of the claimed design.
